UNITED STATES PATENT OFFICE

FRANK A. PIKE, OF ROCHESTER, NEW YORK

SYSTEM OF DRAINING

Application filed January 17, 1928. Serial No. 247,395.

The present invention relates to a system of draining, an object thereof being to keep a cellar or basement floor perfectly dry under any and all conditions of the earth under 5 the floor and that surrounding the foundation wall.

A further object of the invention is the location of a drain in such relation to a foundation wall that water seeping through fissures 10 or in any way passing under and in proximity to the wall will be carried off by the drain and thus prevented from rising under the cellar floor.

A further object of the invention is to afford 15 communication whereby any water seeping through the walls will be carried off by the drain and prevented from running over the floor.

And, a still further object of the invention 20 is the provision of a positive but inexpensive draining system for the purpose specified which is not only adapted for installation when the foundation of a building is under construction but, also, in buildings constructed 25 previous to such installations.

To these and other ends the invention consists of a system of draining as will be fully set forth in the following description and particularly defined in the appended claims.

30 The accompanying drawings illustrating the invention and forming a part of the specification are as follows:

Figure 1 is a horizontal sectional view through the foundation wall of a building 35 equipped with a drain system in accordance with this invention, and which is of the modification of the invention particularly adapted for use in old buildings, that is, in buildings constructed previous to the installation 40 of the drain system.

Fig. 2 is an enlarged vertical sectional view of the mud trap into which the drain discharges and which has a sewer connection.

Fig. 3 is an enlarged vertical sectional de- 45 tail, as on the line 3—3, Fig. 1, through the foundation wall, the cellar floor and the drain.

Fig. 4 is a fragmentary sectional view similar to Fig. 3 but shown in perspective and the method illustrated being a modification of the 50 invention from that shown in Figs. 1 and 3.

Fig. 5 is a fragmentary detail of two adjoining drain tile.

Fig. 6 is an enlarged vertical sectional detail as on the line 6—6, Fig. 8, but showing the modification of the invention employed 55 when the wall is of hollow block construction.

Fig. 7 is a sectional detail on the line 7—7, Fig. 6.

And, Fig. 8 is a plan view of a cellar or 60 foundation wall but showing the modification of the invention preferably used when the drain system is installed during construction of the wall.

In the drawings similar reference numerals refer to similar parts throughout the several views.

It is a very common occurrence for buildings especially dwelling houses to have water in the cellar at times when weather conditions are such that the ground is excessively wet, the water getting into the cellars through cracks in the walls or, in some instances, by seeping through fissures under the foundation and coming up through defective places 70 in the floors. In order to overcome these troubles it has been suggested to seal the walls in one way or another, and it has also been a practice to lay drain tile adjacent the footing of the walls, the latter method, however, 75 often being ineffective owing to the improper placing of the drain with respect to the walls.

The weight of a building compresses the earth for several feet directly under the foundation so as to form an effective seal against 80 water passing through such earth. However, fissures often occur in the earth and water seeping down in proximity to the wall finds these fissures and following them comes up again through the soft earth under the floor. 85 Then, if there are any cracks or porous spots in the floor the result is a wet cellar.

In accomplishing this invention I provide a drain conduit which lies under the cellar floor and adjacent but below the bottom of the footing of the foundation wall, this conduit being endless and paralleling the wall. 90 In old buildings, or rather those in which the system is installed after construction of the buildings, communication to the drain is 95 100

afforded from the floor level inside of and adjacent the foundation wall, and when the system is installed at the time of construction of the buildings this communication to the drain is afforded from approximately the floor level but from the outside of the wall.

Referring first to Figs. 1 to 5, inclusive, which show the modification of the invention as installed in buildings constructed previous to such installation,—the numeral 1 represents a continuous pocket or channel formed just inside of the footing 2 of a foundation wall 3, the bottom of this channel being below that of the footing so that a drain is provided for any water seeping through the earth under and in proximity to the footing. As a conduit for the water porous tile 4 is laid in the channel 1, this tile preferably being what is known to the trade as farm tile, and the depth of the channel is such that this conduit is also below the bottom of the footing 2. This channel 1 has communication through a restricted opening or channel 5 in the floor, preferably against the wall 3 as illustrated, and both the channel 1 and the restricted opening 5 are filled at 6 with cinders, crushed stone or other suitable insoluble material which permits water to readily filter therethrough and pass through the porous wall of the tile. The joints of abutting tile sections may be covered with pieces 7 of fabric or sheet metal to prevent stone or other foreign substance from getting into the conduit and stopping the passage.

From the foregoing it will be observed that any water seeping under the footing 2 will find its way into the channel 1 and filtering through the filling 6 and wall of the tile will be carried off by the conduit 4, and, also, that any water seeping through the wall 3 will run into the channel 5 and likewise be carried off by the conduit. Thus, water is blocked against getting under the floor 8 by the location of the drain at a level below the footing 2, and against getting onto the floor because of the channel 5 which conducts into the drain any water passing through the wall 3.

The conduit 4 discharges through a lateral connection 9 into a mud trap 10 of known construction sunk into the cellar bottom, and from such trap the water passes through a pipe 11 to the sewer 12, a back water trap 13 also of known construction and operation being interposed in the pipe 11 between the mud trap and the sewer. A removable cover 14 is shown as a closure for the mud trap 10.

This modification of the invention may be installed when the building is under construction but if installed in a building previously constructed a portion 8^a of the floor 8 is dug up to permit digging the channel 1 and placing the conduit 4 and filling 6, after which the floor is again relaid to within a few inches of the wall 3 so as to form the narrow chan-

nel 5 which is also filled with the filtering material 6.

In Fig. 4 there is shown a modification of the invention in which the cellar floor 8 adjacent the wall 3 is formed with a channel 8^b, the bottom of such channel having spaced openings 15 through which water falling into the channel 8^b is conducted to the channel 1 and thence to the conduit 4.

Refer now to Figs. 6, 7, and 8.

In this modification of the invention, and also in the ones hereinbefore described if installed during construction of the building, it is recommended that the cellar floor shown at 16 be laid on an approximately three inch layer 17 of cinders or the like, the wall 18 resting upon the footing 19 in the usual manner.

Before the floor is laid a continuous pocket or channel 20 is formed just inside the footing 19, such pocket being similar to and for the same purpose as the channel 1 hereinabove described except that the channel 20 has no channel 5 or other drainage communication through the floor, the latter preferably being continuous to the wall 18. Lying in the bottom of the channel 20 is an endless conduit 21 of drain tile, this preferably being on a level plane below that of the bottom of the footing 19.

Above the footing 19 but in proximity thereto and also to the outer face of the wall 18 and at substantially the floor level is a second or outer endless conduit 22 of drain tile which is parallel to the conduit 21 on all sides of the wall, a space or pocket 23 surrounding the tile and preferably extending a considerable distance up the wall 18, this pocket being filled in with a filtering material 24 of cinders or crushed stone and which is also placed in the channel or pocket 20.

Water accumulating in the pocket 23 and filtering through the filling material 24 seeps through the tile of the conduit 22 and is conducted to the lower and inner channel 1 through laterals 25 which, in this instance, constitute tile sections connecting the two channels 23 and 1, such laterals preferably being equally spaced, arranged on an incline and embedded in the concrete footing 19. The outer ends of the laterals are conformed to the curvature of the tile 22 so that water carried through the laterals will come directly from the conduit 22 and such conduit will block the admission of foreign substance into the laterals. Water entering the channel 1 from the laterals 25 or otherwise seeping thereinto will be carried off by the drain conduit 21.

The outer face of the wall 18 is waterproofed in any suitable manner, such waterproof coating being indicated at 26. In the event, however, of water seeping through the wall and as a further protection when such wall is of hollow block construction, a third

or intermediate conduit 27 is placed at the bottom of the wall 18 and partly embedded in the footing 19 so as to intersect the laterals 25, both intersecting tile being cut out as shown so that water from the drain conduit 27 will run directly into the laterals.

From the foregoing it will be observed that I have provided a positive system of draining for keeping cellars dry; that such system embodies a channel on the inner side of and below the footing so that water seeping through fissures under the footing will pass into the channel; that in one instance additional communication or drainage into this channel is through a communicating channel opening through the cellar floor adjacent the cellar wall; that, in another instance, such communication is through laterals embedded in the foundation footing which lead from a channel or pocket filled with cinders or crushed stone and surrounding the foundation wall; that an endless conduit of drain tile is laid in the outer channel at substantially the floor level and that a like conduit is laid in the inner channel below the bottom of the footing, the first named communicating through said laterals to the second named, and the latter having connection through a mud trap and a back water valve to a sewer; and that, in the event of the wall being of hollow block construction and the outer and inner conduit system used, a third drain conduit of tile is embedded in the footing at the bottom of the wall and in such position as to intersect and discharge into said laterals. It will of course be understood that when the system shown and described with reference to Figs. 6, 7 and 8 is used with a concrete or stone wall of solid construction, the intermediate drain conduit 27 is not employed.

It may also be added that with the herein described system of draining the water is assisted in draining from the soil adjacent a building and simply collected and diverted in its passage so as to prevent it from getting into a cellar and over the floor, while heretofore, to my knowledge, the methods employed have been such as to repel the water.

What I claim is:

1. A system of draining, for the purpose specified, which includes a drain channel under a cellar floor adjacent and parallel to the footing of the foundation wall, a second drain channel parallel to the first named but outside of said wall and at a level above that of the first named channel a filtering material such as crushed stone as a filling for both channels a drain from the upper channel into the lower, and a sewer connection from the lower channel.

2. A system of draining which includes, in combination with a foundation wall, a footing for the wall, and a cellar floor, a channel under said floor filled with a filtering material such as crushed stone, such channel

being adjacent and parallel to the said footing with its bottom below that of the footing, a second channel adjacent said wall and also filled with a filtering material, water connection between the two channels, and an outlet from the first named channel.

3. A system of draining which includes, in combination with a foundation wall, a footing for the wall, and a cellar floor, a channel under said floor filled with a filtering material such as crushed stone, such channel being adjacent and parallel to the said footing with its bottom below that of the footing, a second channel adjacent but outside of said wall and also filled with a filtering material, a water conduit between the two channels and extending on an incline through said footing, and a sewer connection leading from the lower or first named channel.

4. A system of draining which includes, in combination with a foundation wall, a footing for the wall, and a cellar floor, an inner conduit of drain tile under said floor and adjacent and parallel to said footing but on a level below the bottom of the footing, an outer conduit of drain tile adjacent but outside of said wall and at substantially the floor level, filtering material such as crushed stone surrounding said conduits, lateral connections between the two conduits and arranged in said footing, and a sewer connection leading from said inner conduit and including a mud trap and a back water valve.

5. A system of draining in accordance with claim 4 characterized by said lateral connections being tile sections embedded in and extending on an incline through said footing.

6. A system of draining which includes, in combination with a foundation wall of hollow construction, a footing for the wall, and a cellar floor, an inner conduit of drain tile under said floor and adjacent and parallel to said footing but on a level below the bottom of the footing, an outer conduit of drain tile but outside of said wall and at substantially the floor level, filtering material such as crushed stone surrounding said conduits, lateral connections between the two conduits and arranged in said footing, an intermediate conduit of drain tile embedded in said footing at the bottom of said wall, such latter conduit intersecting and opening into said lateral connections, and a sewer connection leading from said inner conduit.

7. A system of draining in accordance with claim 4 characterized by said lateral connections being tile sections embedded in and extending on an incline through said footing, and said tile sections at their outer ends being conformed to the curvature of the tile of the outer conduit.

8. A system of draining, for the purpose specified, which includes a channel under a cellar floor adjacent and parallel to the foot-

ing of the foundation wall, a filtering material such as crushed stone as a filling for said channel, a drain adjacent and parallel to the cellar wall at the floor level, a water connection between the drain and said channel, and 5 an outlet from the channel, the bottom of the channel being below that of the footing.
